FAUCET HANDLE

Ralph E. Thorp, Lafayette, Ind., assignor to Globe Valve Corporation

Filed Feb. 3, 1972, Ser. No. 223,393

Term of patent 14 years

Int. Cl. D23—01

U.S. Cl. D23—28

FIG. 2

FIG. 1 is a top plan view of a faucet handle, showing my new design; and

FIG. 2 is a side elevational view, all sides being the same.

I claim:

The ornamental design for a faucet handle, substantially as shown and described.
